(57) CLAIM

The ornamental design for a water spray nozzle link, as shown and described.

DESCRIPTION

The present design relates to a link of a water spray nozzle for use in gardening and cleaning.

FIG. 1 is a perspective view of a water spray nozzle link of the present design;

FIG. 2 is a front (or back) view of the water spray nozzle link of FIG. 1;

FIG. 3 is a left-hand side (or right-hand side) view of the water spray nozzle link of FIG. 1;

FIG. 4 is a top view of the water spray nozzle link of FIG. 1;

FIG. 5 is a bottom view of the water spray nozzle link of FIG. 1; and,

FIG. 6 is a front view of a water spray nozzle incorporating the water spray nozzle link of the present design of FIGS. 1-5.

In FIG. 6, elements shown in broken lines provide an environmental structure in which the water spray nozzle link of the present design is used, and do not form part of the claimed design.
